UNITED STATES PATENT OFFICE.

HENRY P. CLAUSEN, OF MOUNT VERNON, NEW YORK, ASSIGNEE TO WESTERN ELECTRIC COMPANY, INCORPORATED, OF NEW YORK, N. Y., A CORPORATION OF NEW YORK.

TELEPHONE SYSTEM.

1,295,435.

Specification of Letters Patent. Patented Feb. 25, 1919.

Application filed July 26, 1917. Serial No. 162,945.

To all whom it may concern:

Be it known that I, HENRY P. CLAUSEN, a citizen of the United States, residing at Mount Vernon, in the county of Westchester and State of New York, have invented certain new and useful improvements in Telephone Systems, of which the following is a full, clear, concise, and exact description.

10 This invention relates to telephone systems, and more particularly to telephone systems employing machine switches to establish the whole or part of the connection.

15 In extending calls from an exchange to a private branch exchange, it has been found that it frequently arises that the original called party is unable to give all the information required, and it is necessary for him to call a second party in the exchange to ascertain the desired information. In dealing with this contingency, it is necessary for the original called party in obtaining information from the second party to inform the calling party to disconnect and that he will call him up later.

In accordance with the present invention, it is proposed to provide means whereby the calling party's connection to a private branch exchange may be maintained while the called party obtains connections without the aid of an operator and converses with a third party.

Figure 1 diagrammatically illustrates a portion of a telephone system employing the present invention. The portion of the drawing at the left of the broken line represents a calling substation which may be connected by any suitable means with a private branch exchange, and, through the agency of an operator, with one of a number of lines, all of which is indicated at the right of the broken line.

Fig. 2 diagrammatically illustrates a portion of a telephone system employing the present invention, in which the connection is set up automatically. The portion of the drawing at the left of the broken line in Fig. 2 diagrammatically represents a calling line at a distant exchange which may be automatically extended to the connector switch circuit at the private branch exchange, indicated at the right of the broken line.

Referring to Fig. 1, the calling subscriber, whose substation is illustrated at A, may be connected, through a distant exchange (not

shown), to the jack 100 at the operator's position of the private branch exchange. As soon as the calling line has been extended to the operator's position, a signal is operated in the well known manner, in response to which the operator inserts the answering plug 101 of her cord circuit into the jack 100. The private branch exchange operator may then depress a listening key (not shown) to connect her headset (not shown) to the calling line to ascertain the number of the desired party. Let it be assumed that the desired line terminates in the jack 103. The operator thereupon inserts the calling plug 102 into the jack 103 of the called subscriber's line. The called subscriber may then be signaled in any well known manner. As soon as the plug 102 is inserted into the jack 103, the cut-off relay 104, individual to the line of subscriber B, is energized over a circuit extending from grounded battery, winding of relay 104, conductor 105, contact 106, spring 107, sleeve 103 of the jack, sleeve 102 of the plug, conductor 108, through either of the right-hand back contacts and armatures of relays 109, 110 and 111, winding of relay 112, to ground. The cut-off relay operates to disconnect the line relay 113 before it can energize the plunger operating magnet 114 of the line switch. If, now, the called party B wishes to communicate with the subscriber C of his own private branch exchange, it is necessary for him to operate his sending device 119 to transmit a predetermined number of impulses to bring about the deenergization of the cut-off relay 104. This causes the line relay 113 to energize to effect the operation of the line switch or non-numerical switch. The subscriber B then operates his sending device to transmit impulses corresponding to the designation of a third line connected with substation C.

In considering the operation of seizing a non-numerical switch or line switch as a result of the deenergization of the cut-off relay 104, it will be noted that the energizing circuit of this relay normally has several alternate paths extending through the right-hand back contacts and armatures of relays 106, 110 and 111. It is, therefore, necessary to simultaneously energize these relays and to bring about the deenergization of the relay 115 before the cut-off relay 104 is rendered inert. As soon as B's line is connected to the calling line, the relay 115 is 110

206 is energized over a circuit extending from grounded battery, side-switch wiper 208 in its first position, inner contact and armature of relay 202, back contact and armature of relay 200 to ground.

At the close of the tens series of impulses, the relay 200 attracts its armature for a relatively long interval to bring about the deenergization of the relay 203. The energizing circuit of the escape magnet 204 is thus interrupted and this magnet moves its side-switch wipers into their second position. The calling subscriber now operates the sending device 201 to transmit impulses corresponding to the units digit of the desired number. In response to these impulses, the line relay 200 vibrates its armature, and, at the first retraction of its armature, again closes an energizing circuit for relay 203. The energizing circuit of the escape magnet 204 is thereby again established. As the line relay 200 retracts its armature in response to each impulse, the secondary magnet is energized over a circuit from grounded battery, winding of this magnet, side-switch wiper 208 (second position), inner front contact and armature to relay 202, back contact and armature of relay 200, to ground. The secondary motor magnet 207 advances the brushes 209, 210 and 211 over the terminals of the selected group. At the close of the units series of impulses, the relay 203 retracts its armature to interrupt the energizing circuit of the escape magnet 204. The escape magnet 204, on deenergizing, moves its side-switch wipers into their third position. The relay 216 is then energized from grounded battery, winding of this relay, right-hand armature and contact of relay 229, side-switch wipers 234 and 233, left-hand armature and contact of relay 229 to ground.

In this position of the side-switch wipers the relay 203 is energized over a circuit now traced from grounded battery, winding of this relay, side-switch wiper 208 (third position), conductor 212, front contact and armature of relay 200, which is now energized, to ground. Relay 203, by attracting its right-hand armature, reestablishes the energizing circuit to the escape magnet 204. The escape magnet 204 attracts its armature and thereby completes a circuit for signaling the called substation B. This circuit is traceable from grounded battery, through the generator 213, winding of the marginal ringing trip relay 205, contact and armature of escape magnet 204, conductor 214, side-switch wiper 215 (third position), lower armature and contact of relay 216, connecting brush 210, through the terminal and ring conductor of B's line, through the substation circuit, tip conductor and terminal of B's line, connector brush 209, contact and upper armature of relay 216, side switch-wiper 217

(third position), conductors 218 and 212, front contact and armature of relay 200, to ground. When the subscriber B removes his receiver from the switchhook, sufficient current passes through the winding of the marginal relay 205 to cause it to attract its armature. This interrupts the energizing circuit of the escape magnet 204, and this magnet moves the side-switch wipers into their fourth or talking position.

When the side-switch wipers reach their fourth position, the relay 220 is energized over a circuit traced from grounded battery, right-hand winding of relay 220, side-switch wiper 215, lower armature and contact of relay 216, brush 210, the connector terminal and lower side of the called subscriber's line, through the substation B, upper side of the line, terminal connector brush 209, contact and upper armature of relay 216, side-switch wiper 217 (fourth position), left-hand winding of relay 220, to ground. It will be noted that the talking current of the called subscriber is supplied through the windings of relay 220. If, now, the subscriber at substation B desires to converse with the subscriber at substation C, it is necessary that his cut-off relay 221 be deenergized in order to reconnect the line relay 222 to his line. This is accomplished by the subscriber at substation B operating his sending device 223 to transmit a predetermined number of impulses. When the relay 220 deenergizes in response to the first impulse from the sending device, the slow releasing relay 226 becomes energized over a circuit extending from grounded battery, winding of this relay, outer left-hand back contact and armature of relay 227, inner right-hand back contact and armature of relay 220, side-switch wiper 225 (fourth position), to ground. The relay 226 attracts its armatures and when the relay 220 attracts its armature at the close of the first impulse from the sending device, a circuit is completed through grounded battery, inner right-hand contact and armature of relay 226, winding of the slow releasing relay 227, inner front contact and armature of relay 220, side-switch wiper 225, to ground. Relay 227 is energized in this circuit and attracts its armatures. When the relay 220 deenergizes in response to the next impulse from the sending device 223, slow releasing relay 228 is energized over a circuit completed from grounded battery, winding of this relay, outer left-hand front contact and armature of relay 227, left-hand back contact and armature of relay 220, side-switch wiper 225 (fourth position), to ground. It will now be seen that the slow releasing relays 226, 227 and 228 have been energized. As a result of operation of these relays an energizing circuit is completed for the relay 229. This circuit may be traced from 130

grounded battery, winding of the relay 229, conductor 232 through the left-hand front contacts and armatures of relays 228 and 226, inner left-hand front contact and armature of relay 227, side-switch wiper 225 to ground. The relay 229 attracts its armatures. It should be noted that the circuit through the left-hand front contact and armature of relay 229 is interrupted before the circuit is completed through the right-hand front contact and armature of this relay. This prevents the cut-off relay from remaining energized in parallel with relay 229 over conductor 232. The cut-off relay 221 has its energizing circuit interrupted at the left-hand armature and contact of relay 229 and retracts its armatures to connect the line relay 222 to B's line. The line relay 222 in operating causes the line switch, which is diagrammatically indicated at 230, to connect B's line to an idle selecting switch diagrammatically indicated at 231. The line switch 230 in operating causes the operation of the cut-off relay 221 due to ground on lead 240. The relay 229 is also energized in parallel with the cut-off relay over a circuit traceable from the grounded battery, winding of the relay 229, right-hand front contact and armature of this relay, test brush 211 of the connector to ground through the contact springs of the line switch 230. It will be seen that the relay 229 at its right-hand back contact and armature interrupts the energizing circuit of the relay 216. The relay 216 on deenergizing opens the contacts of the conversational circuit which connects the subscribers at stations A and B.

When the subscriber at station B desires to disestablish his connection with the subscriber at station C, he momentarily replaces his receiver on its switchhook. This operation causes the line switch to restore and the other switches employed in establishing the connection to C substation to be restored in the well known manner. The release of the line switch 230 causes the momentary deenergization of the cut-off relay 221, and also causes the deenergization of the relay 229. The subscriber at station B then immediately removes his receiver from its switchhook. The cut-off relay 221 is now energized over a circuit extending from grounded battery, winding of the cut-off relay, test terminal and test brush 211, side switch wiper 233 in its fourth position, left-hand armature and contact of relay 229 and to ground through one of a plurality of paths completed through the right-hand armatures and back contacts of relays 220, 227, 226 and 228. The relay 216 is also energized in parallel with the cut-off relay over a circuit traceable from grounded battery, winding of the relay 216, right-hand armature and back contact of relay 229, side switch wiper

234 in its fourth position, side switch wiper 233 in its fourth position over the remainder of the circuit previously described to ground. The relay 216 in attracting its armatures again completes the conversational circuit 70 between the substations A and B.

At the close of the conversation the restoration of the connector switch, which is under the control of the calling subscriber, is brought about by the subscriber at substation A replacing his receiver on its switchhook. In response to this operation the relay 200 retracts its armature. This interrupts the energizing circuit of the slow releasing relay 202, causing it, after 80 a brief interval, to retract its armatures. An energizing circuit is thereupon completed for the release magnet 235 of the connector. This circuit extends from grounded battery, right-hand winding of 85 the relay 235, off-normal contact 236, inner left-hand back contact and armature of relay 202, back contact and armature of relay 200 to ground.

If the desired line leading to the substation at B was found to be busy, the relay 235 is energized to bring about the restoration of a connector switch and to apply a busy tone. The energizing circuit of the release magnet 235 is then completed from 95 grounded battery, right-hand winding of the release magnet 235, off-normal contact 236, left-hand armature and contact of relay 203, side-switch wiper 234 in its second position, to ground over a multiple test contact. 100 Magnet 235 on attracting its armatures completes a locking circuit for itself from grounded battery through its left-hand winding and its left-hand contact and armature, conductor 212, front contact and 105 armature of relay 200 to ground. As a result of a completion of this last traced circuit, the release magnet 235 releases the connector switch and through its right-hand armature and contact applies a busy tone 110 to the calling line; this tone is applied until the calling subscriber replaces the receiver on its switchhook. As a result the line relay 200 retracts its armature to break the locking circuit of the release magnet 235. 115

What is claimed is:

1. In a telephone system, a plurality of stations, means for establishing a connection from one of said stations to a second station, means for interconnecting the second station with a third station and for discontinuing the talking connection from the first named station while said second and third stations are interconnected, means to disconnect said third station, and means 124 controlled by said disconnection for re-establishing the connection between the first and second stations.
2. In a telephone system, a plurality of stations, means for establishing a connec- 128

tion from one of said stations to a second station, means for interconnecting the second station with a third station and for discontinuing the talking connection from the 5 first named station while said second and third stations are interconnected, means for releasing either of the established connections, and means controlled by the release of one of said connections for reestablishing the connection between the first and second stations.

3. In a telephone system, a plurality of stations, an impulse sending device at each station, means for establishing a connection from one of said stations to a second station, means controlled by the sending device at the second station for interconnecting the same with a third station and for discontinuing the talking connection from the 10 first named station while said second and third stations are interconnected, means to disconnect said third station, and means controlled by said disconnection for reestablishing the connection between the 20 first and second stations.

4. In a telephone system, a plurality of stations, means for automatically establishing a connection from one of said stations to a second station, means for interconnecting the second station with a third station and for discontinuing the talking connection from the first named station while said second and third stations are interconnected, means to disconnect said third station, and means controlled by said disconnection for automatically reestablishing the talking connection between the first and second stations.

5. In a telephone system, a plurality of 40 stations, an impulse sending device at each station, means for establishing a connection from one of said stations to a second station, means controlled by the sending device at the second station for interconnecting the same with a third station and for discontinuing the talking connection from the first named station while said second and third stations are interconnected, means for releasing either of the 45 established connections, and means controlled by the release of one of said connections for reestablishing the connection between the first and second stations.

6. In a telephone system, a plurality of 55 stations, an impulse sending device at each station, switches for establishing a connection from one of said stations to a second station, electromagnetic means for operating said switches, other switches controlled 60 by the sending device at the second station for interconnecting the same with a third station, means actuated upon operation of said other switches for discontinuing the talking connection from the first named station 65 while the second and third stations are

interconnected, means to disconnect said third station, and means controlled by said disconnection for reestablishing the talking connection between the first and second named stations.

7. In a telephone system, a plurality of stations, means for completing a conversational circuit from one of said stations to a second station, means controlled from said second station for initiating a connection to 70 a third station and for rendering said circuit ineffective without disestablishing the connection between the first and second stations while the second and third stations are connected, and means for automatically completing the connection initiated from the second station.

8. In a telephone system, a plurality of stations, impulse transmitting devices associated with certain of said stations, means 80 for completing a conversational circuit from one of said stations to a second station, means controlled by the impulse transmitting device at said second station for initiating a connection to a third station and for rendering said circuit ineffective without disestablishing the connection between the first and second stations while the second and third stations are connected, and means for completing the connection initiated from said 90 second station.

9. In a telephone system, an incoming line, a plurality of outgoing lines, means for interconnecting said incoming line with an outgoing line, mechanism normally maintaining said outgoing line inoperative as an incoming line while it is connected to said incoming line, means controlled over said outgoing line for rendering said mechanism ineffective, means for connecting said outgoing line to a second outgoing line, and means for releasing the established connections.

10. In a telephone system, an incoming line and plurality of outgoing lines, an impulse transmitting device associated with each of said outgoing lines, means for interconnecting said incoming line with any of said outgoing lines, mechanism normally maintaining the selected outgoing line inoperative as an incoming line while it is connected to said incoming line, means controlled by said impulse transmitting device for rendering said mechanism ineffective, means for connecting said outgoing line to a 110 second outgoing line, and means for releasing the established connections.

11. In a telephone system, an incoming line, a plurality of outgoing lines, a cut-off relay and a line relay individual to each of 125 said outgoing lines, said cut-off relay operating to remove the control of said line relay from its associated line, means for interconnecting said incoming line with any of said outgoing lines, means operative thereupon to 130

operate said cut-off relay, mechanism controlled from the selected outgoing line while the original connection is maintained to cause the selected line to regain control of its line relay, and means to interconnect said selected outgoing line with a second outgoing line.

12. In a telephone system, an incoming line, a plurality of outgoing lines, an impulse transmitting device associated with each of said outgoing lines, a cut-off relay and a line relay individual to each of said outgoing lines, said cut-off relay operating to remove the control of said line relay from its associated line, means for interconnecting said incoming line with any of said outgoing lines, means operative thereupon to operate said cut-off relay, mechanism controlled from the impulse transmitting device associated with the selected line while the original connection is maintained to cause the selected line to regain control of its line relay, and means to interconnect said selected outgoing line with a second outgoing line.

13. In a telephone system, an incoming line, a plurality of outgoing lines, a cut-off relay and a line relay controlled thereby associated with each of said outgoing lines, means for interconnecting said incoming line with any of said outgoing lines, means oper-

ative thereupon to effect the operation of said cut-off relay and the deenergization of said line relay, mechanism controlled from the selected outgoing line while the connection is maintained for reversing the condition of said line and cut-off relays associated therewith to initiate a second connection, and means to complete the initiated connection.

14. In a telephone system, an incoming line, a plurality of outgoing lines, an impulse transmitting device associated with each of said outgoing lines, a cut-off relay and a line relay controlled thereby associated with each of said outgoing lines, means for interconnecting said incoming line with any of said outgoing lines, means operative thereupon to effect the operation of said cut-off relay and the deenergization of said line relay, mechanism controlled from the impulse transmitting device associated with the selected outgoing line, said mechanism operating while the connection is maintained for reversing the condition of said line relay and said cut-off relay to initiate a second connection, and means to complete the initiated connection.

In witness whereof, I hereunto subscribe my name this 24th day of July, A. D. 1917.

HENRY P. CLAUSEN.
